UNITED STATES PATENT OFFICE.

HERMANN GENSCHE, OF BONITA, ARIZONA, ASSIGNOR OF ONE-HALF TO A. J. MILLS, OF BONITA, ARIZONA.

HAT-RETAINER.

1,276,052.

Specification of Letters Patent. Patented Aug. 20, 1918.

Application filed May 25, 1917. Serial No. 171,016.

To all whom it may concern:

Be it known that I, HERMANN GENSCHE, a citizen of the United States, residing at Bonita, in the county of Graham and State of Arizona, have invented new and useful Improvements in Hat-Retainers, of which the following is a specification.

This invention relates to improvements in hat fastening devices, and has for its object 10 to produce an attachment which may be readily secured to hats or caps for women or children to engage in the hair of the wearer and to prevent the hat from being blown or accidentally removed from the 15 head of the wearer.

It is an object of the invention to produce a device of this class which shall be of a simple construction, ornamental in character, light and durable and which can be 20 easily and quickly applied to the hair of the wearer without inconvenience or injury.

With the above and other objects in view the improvement resides in the construction, combination and arrangement of parts 25 set forth in the following specification and falling within the scope of the appended claims.

In the drawings:

Figure 1 is a view illustrating the application of the improvement,

Fig. 2 is a central vertical longitudinal sectional view through a hat provided with the improvement,

Fig. 3 is a bottom plan view of the same, 35 Fig. 4 is a sectional view approximately on the line 4—4 of Fig. 2,

Fig. 5 is a perspective view of the comb member and the attaching plate thereto,

Fig. 6 is a bottom plan view of a hat provided with a modified form of the device,

Fig. 7 is an approximately central longitudinal section view through the same,

Fig. 8 is a plan view illustrating a still further modification, and

Fig. 9 is a detail perspective view of one of the adjustable comb members.

In the drawing the numeral 1 designates a lady's hat of any ordinary construction and which has secured to the sweat band and 50 if desired also to the hat, at the front thereof, a plate 2. The plate comprises an angle member, the portion thereof secured to the hat conforming to the shape of the hat, and the offset portion being formed with or having secured thereto a longitudinally extend-

ing comb member 3. To the hat band and if desired to the hat, at the rear portion thereof, and at diametrically opposite points upon the rear portion is secured the ends of an elastic band 3. The numeral 4 designates a rounded plate or barrette 5 which may be and preferably is of an ornamental nature, the same being provided at its ends with openings 6 through which the elastic member 3 passes so that the plate 4 may be adjusted longitudinally upon the said elastic member 3.

In applying the device the hat is so arranged that the teeth of the comb 3 are inserted in the hair of the wearer at the front 70 of the head and the hat is then gently pulled down to a comfortable position. The plate 4 is then drawn downwardly from its elastic connection and brought to a convenient position upon the back of the head of the 75 wearer.

In removing the hat the barrette is drawn away from its engaging position to permit 80 of the hat being moved outwardly of the head of the wearer.

In Fig. 7, in addition to the front permanently secured comb the elastically connected plate or barrette I have illustrated auxiliary or side combs 7 and 8, each provided with a handle portion 9, the ends of the 85 comb members 8 being provided with openings through which is passed elastic members 10 that have their ends secured to the hat, as at 11. The central portion of the elastic members 10 pass over the outer edge 90 of the comb and contact with the outwardly rounded surface of the handle members, and this is attached in a manner similar to that previously described except that the side comb members are drawn upon their 95 elastic connections and the teeth thereof permitted to be inserted by the influence of the said elastic members into the hair of the wearer at the sides thereof and, of course, withdrawn when the hat is to be 100 removed.

It is to be understood that if desired the stationary comb member may be dispensed with as may also the rear plate or barrette and that in lieu thereof a plurality of elastically secured comb members similar to the members illustrated in Figs. 7 and 8 may be employed, the said elastic members having their ends secured in any desired position in the hat and as the said combs are 110

slidably arranged upon the said elastic members it will be noted that the combs may be inserted in the hair at any desired point with respect to the angle at which the hat 5 is to be sustained upon the head of the wearer and with respect to the comfort of the wearer.

In Fig. 8 of the drawings, the stationary comb is dispensed with and the slideable 10 combs 12 are arranged upon elastic members 13 which have their ends secured, as at 14, at suitable points in the hat band. These combs as illustrated in Fig. 9 of the drawings being provided with centrally extending 15 angular elements providing handles 15 whereby the same may be grasped by the operator and readily removed.

While the device has been described in connection with women and children's head 20 gear, it is to be understood that the same may, with slight modifications, be equally adaptable for use upon men's or boys' head gear. It is also to be understood that the comb may, if desired, be constructed of a 25 single element and that the barrette as well as the combs may be arranged in positions different from that illustrated in the drawings.

Having thus described the invention, what 30 I claim is:

1. A hat retainer comprising a horizontally extending comb rigidly secured within the front portion of a hat, an elastic member having its ends secured within the 35 hat, and an arcuate plate provided with spaced holes through which said elastic member is trained whereby said plate will be adjustable longitudinally of said elastic member.

40 2. A hat retainer comprising an angular

plate having its vertical portion secured within the front of a hat, a rearwardly extending horizontally disposed comb rigidly secured upon the horizontal portion of said angular plate, an elastic member having its ends secured upon the inner sides of the hat, and an arcuate plate having its end portions provided with holes through which said elastic member is trained whereby said plate may be adjusted longitudinally of 45 said elastic member.

3. A hat retainer comprising a comb rigidly secured in horizontal position within the front portion of a hat, an elastic member having its ends secured upon the inner 50 sides of the hat, an arcuate plate disposed at the rear portion of the hat and slidably connected with said elastic member, and a pair of combs disposed at the sides of the hat with their teeth in inwardly extending 55 relation and provided with holes through which said elastic member is trained whereby said comb members may be longitudinally adjustable of said elastic member.

4. A hat retainer comprising a horizontally extending comb secured within the front portion of a hat, an elastic member having its ends secured upon the inner sides of the hat, and a pair of comb members disposed at opposite sides of the hat and 60 provided at their end portions with holes through which said elastic member is trained, and outwardly extending projections on the backs of said last named combs 65 engaged by said elastic member for urging the teeth of said comb in a direction toward the crown of the hat.

In testimony whereof I affix my signature.

HERMANN GEN SCH.
